UNITED STATES PATENT OFFICE.

WILLIAM V. ROBINSON, OF DETROIT, MICHIGAN, ASSIGNOR TO ART STOVE COMPANY, OF DETROIT, MICHIGAN, A CORPORATION OF MICHIGAN.

DESIGN FOR A STOVE.

SPECIFICATION forming part of Design No. 35,954, dated June 17, 1902.

Application filed December 30, 1901. Serial No. 87,854. Term of patent 7 years.

To all whom it may concern:

Be it known that I, WILLIAM V. ROBINSON, a citizen of the United States, residing at Detroit, in the county of Wayne and State of Michigan, have invented and produced a certain new and original Design for a Stove, of which the following is a specification, reference being had therein to the accompanying drawings, in which the stove is shown in perspective.

The reference-letter A designates the stove-body, rectangular in configuration and flaring outwardly at its lower edge, forming the tapering base-section B. Upon the front face 15 of the body are the rectangular doors D and E, arranged in vertical alinement at one side of the front, and a similar door F, occupying substantially the central portion of the stove-front and provided with the ornamental 20 hinges F² and fastener or catch F³. Below the central door described are ornamental plates F' and G, and intermediate the doors D and E is an ornamental panel H.

I represents a similar panel beneath the 25 lower door E, and J represents ornamental corner-pieces upon the base-section, as shown.

K designates a rectangular water-tank at one side of the stove-body, supported by an ornamental bracket M, and N designates the 30 stove-top, extending over the body and tank, as indicated. At the side of the stove-body opposite the tank is the flue-door O, and above this door is a draft-section P, bulging outwardly from the body at its lower end and 35 tapering inwardly at its upper end.

Q designates a broiler-section overhanging the draft-section, as illustrated, and provided with an ornamental door R. The sides of the draft and broiler sections adjacent to the stove-front are ornamented with scroll-work R'.

Rising from the sides of the stove-top are shelf-brackets S, which support the warming-shelf T, and U designates a back plate or panel rising from the rear edge of the stove-top and projecting upward beyond the shelf, as shown.

V designates the smoke-pipe, arranged immediately adjacent to the panel U and midway between the shelf-supporting brackets.

W designates ornamental figures arranged upon the panel U on opposite sides of the pipe, and X is an ornamental figure upon the front of the pipe beneath the shelf.

Y designates ornamental corner-pieces upon the upper corners of the panel U.

The leading features of this design reside in the general configuration of the stove as a whole and in the ornamentation thereof, as illustrated.

What I claim as my invention is—

The design for a stove, substantially as herein shown and described.

In testimony whereof I affix my signature in presence of two witnesses.

WILLIAM V. ROBINSON.
